United States Patent Office

Des. 199,039
Patented Sept. 1, 1964

199,039

CLAMP

George W. Bolinger, Jr., P.O. Box 214, Rte. 1,
Cortland, Ohio

Filed Mar. 18, 1964, Ser. No. 79,054

Term of patent 14 years

(Cl. D54—13)

Fig. 1.

Fig. 2.

Fig. 3.

FIGURE 1 is a plan view of a clamp showing my new design, and

FIGURES 2 and 3 are sectional views respectively corresponding to the lines 2—2 and 3—3 of FIGURE 1.

The dominant features of my design reside in the portions shown in full lines.

I claim:

The ornamental design for a clamp, substantially as shown and described.
